Warren D. Witt, 5595 Lemon Ave.,
Long Beach, Calif. 90805

Filed May 20, 1968, Ser. No. 12,000

Term of patent 3½ years

Int. Cl. D12—14

U.S. Cl. D71—1

FIG.1

FIG.7

FIG. 1 is a perspective view of a mast holder for surfboard showing my new design;

FIG. 2 is a top plan view thereof;

FIG. 3 is a left side elevational view thereof;

FIG. 4 is a right side elevational view thereof;

FIG. 5 is a front elevational view thereof;

FIG. 6 is a rear elevational view thereof; and

FIG. 7 is a bottom plan view thereof.

I claim:

The ornamental design for a mast holder for surfboard, substantially as shown and described.
